UNITED STATES PATENT OFFICE

ABRAHAM M. BABITCH, OF FLINT, MICHIGAN, ASSIGNOR TO A C SPARK PLUG COMPANY, OF FLINT, MICHIGAN, A COMPANY OF MICHIGAN

PUMP DRIVE

Application filed July 7, 1928. Serial No. 280,964.

This invention relates to a drive for a fuel pump of a type that is currently used upon internal combustion engines, and the like; and it is an object of this invention to provide a variable-stroke pump with improved actuating means including a shaft having a bearing in a pump body and provided with means for its rotation from some suitably rotating part usually included in an automotive organization. The rotative part referred to may be such as the crank shaft or cam shaft of an engine, a generator shaft, a centrifugal pump shaft, a distributor shaft,—in fact, any rotating member included in or associated with the power plant of a motor vehicle or the like and disposed either coaxially with or at an angle to the first-mentioned shaft.

A variable-stroke fuel pump being described and claimed in a copending application (S. N. 123,370, filed July 19, 1926) a thrust-refusing intermediate means comprising a linkage is used therein conditionally to transmit motion,—to effect the intake stroke of a pumping element in the form of a flexible diaphragm; but a lever, extending from an engine casing into a pump body and uniformly oscillated by means such as a cam on a crank shaft or on a cam shaft, is therefore used as an actuating element for said linkage; and it is an object of my present invention, obviating use of such a lever (and all necessity for the large opening required therefor) to employ a rotated actuating element, extending into the pump body and there carrying an eccentric part to impart movement to thrust-refusing intermediate means such as the mentioned linkage.

Other objects of this invention, which may ordinarily involve the provision of a bearing or bearings in the mentioned pump body for the mentioned pump-actuating shaft, and in which said shaft may ordinarily be horizontally disposed and terminated within the mentioned housing, being there provided

with a crank or cam, may be best appreciated from the following description of alternative embodiments thereof, taken in connection with the appended claims and the accompanying drawings.

Fig. 1 is, for the most part, an elevational view, parts being broken away to a substantially median plane.

Fig. 2 is a partial vertical sectional view, taken substantially as indicated by the arrow 2 of Fig. 1.

Fig. 3 is a view similar to Fig. 2, but showing alternative features hereinafter described.

Figs. 4 and 5 are respectively views showing mechanical trains suggested as respectively suitable for use in transmitting motion from a horizontal shaft and from a vertical shaft, with or without a speed-reducing effect, to a horizontal pump-actuating shaft such as that which is shown centrally in Fig. 1,—bearing and associated parts being omitted.

Referring first to the conventional part of that embodiment of the present invention which is shown in Figs. 1 and 2, a main casting or pump body 10 and a cover casting 11 are shown as co-operating in the retention of a reciprocable pumping element in the form of a flexible diaphragm 12. The cover casting 11 is shown as carrying not only an inlet valve organization at 13 and an outlet valve organization at 14 but also a sight cup or filter cup 15,—the construction here referred to being such that, upon reciprocation of the diaphragm 12, liquid fuel entering through a pipe 16 and passing through the cup 15 and past the valve at 13 may enter a pump chamber 17, to exit therefrom past valve 14 and through an outlet 18,—adapted to receive a delivery pipe leading to a carburetor (not shown).

Expulsion strokes being preferably imparted to the diaphragm 12, or its equivalent, by resilient means such as a compression spring 19 (and the action of this spring being condi-

tioned upon the amount of pressure built up within the pump chamber 17) intermediate thrust-refusing means such as a slidable rod 20 and links 21 and 22 may be employed to impose part intake movements to said diaphragm, subject to actuation by means such as are next to be described.

The main pump body casting 10, serving to house any suitable thrust-refusing means, 10 may comprise also a lateral bearing extension 23,—shown as rigidly connected therewith by means comprising a diagonal re-enforcing web 24 and as adapted to receive a rotatable element in the form of a shaft 25; 15 and the latter is designed to serve as, or to be comprised in, actuating means for the thrust-refusing linkage above referred to. For example, assuming the shaft 25 to inwardly terminate in a wrist-pin 26, this wrist-pin 20 may be received in a suitable aperture in the lower end of the link 22, substantially as illustrated in Figs. 1 and 2. Alternatively, assuming the shaft 25 to inwardly terminate in or to be provided with an eccentric element 25 in the form of a cam 26', the latter may engage a lever 27, shown as pivoted at 28 to the lever 22 and as pivoted at 29 to a main casting 10',—said lever being positioned entirely within the main casting and being preferably provided with resilient means, such as a compression spring 30, adapted to hold the same at all times in contact with the cam 26'.

The shaft 25 may be provided at its end 35 opposite from the crank pin 26 or the cam 26' with means such as key or joint 31, adapting the same to be engaged by, for example, a shaft 32 included in some generator 33, or the like.

40 In Fig. 4, the shaft 25, although still horizontal, is shown as driven from an additional horizontal shaft 34, extending substantially at right angles thereto, by means comprising a worm gear 35 upon the former shaft and a 45 worm 36 upon the shaft 34; and in Fig. 5, in order to drive the horizontal shaft 25 from a substantially vertical shaft 34', the shafts 25 and 34' are shown as respectively provided with beveled gears 35' and 36'.

50 The general mode of operation of a pump of the described character being obvious from the foregoing, and the main features thereof being fully set forth in my mentioned pending application, it will be understood 55 that as soon as operation of a pump of the described character builds up a pressure within the pump chamber 17 such pressure tends to hold the diaphragm 12 against upward movement,—the stroke of the pumping 60 element being thereby rendered variable; but my present invention relates exclusively to the use of a rotatable element such as the shaft 25 in actuating a reciprocating pump element,—a stroke thereof being preferably 65 variable and preferably effected through

means such as a slidable rod and links, or the like, disposed in a plane at an angle to the axis of said shaft.

The construction illustrated in Figs. 1 and 2 (all of the described constructions being 70 adapted to make use of some eccentric element upon or near the inner end of a shaft 25) has the advantage of simplicity; but it will be obvious that a long stroke may be provided for by means such as are illustrated in Fig. 75 3; and obvious also that either the crank-pin construction of Figs. 1 and 2 or the cam-and-lever construction of Fig. 3 may be employed in organizations such as are suggested in Figs. 4 and 5,—the latter being intended primarily 80 to illustrate the practicability of driving the shaft 25, or its equivalent, from a shaft disposed at an angle thereto and the practicability of incidentally effecting any desired 85 change in the rate of rotation of the pump-actuating shaft 25, as compared with that of any shaft from which power may be taken.

Although but a limited number of embodiments of the present invention are above described, it will be obvious that numerous additional modifications thereof might easily be devised by workers in the arts to which this case relates,—without involving the least departure from the scope of the invention as indicated above and in the following claims. 90

I claim:

1. In a fuel pump of the class described, a hollow body part having a laterally extending bearing for a rotatable shaft adjacent its lower end, a cover fastened to the upper end 100 of said body part, a flexible pumping diaphragm held between said cover and upper end, a reciprocating operating rod the upper end of which is connected with said diaphragm, a guide for said rod, a spring surrounding said operating rod and acting to force it and said diaphragm upward, two links arranged as a toggle, said links being pivotally connected together and the upper end of the upper of them being pivotally connected with the lower end of said operating rod, a third link one end of which is pivotally supported within said pump body, and the other end of which is pivotally connected with the lower end of the lower one of said 110 two links, and a shaft rotatable in the bearing aforesaid and the inner end of which is operatively associated with said third link.

2. In a fuel pump of the class described, a hollow body part having a laterally extending bearing for a rotatable shaft adjacent its lower end, a cover fastened to the upper end 120 of said body part, a flexible pumping diaphragm held between said cover and upper end, a reciprocating operating rod the upper end of which is connected with said diaphragm, a guide for said rod, a spring surrounding said operating rod and acting to force it and said diaphragm upward, two links arranged as a toggle, said links being 125 130

pivots connected together and the upper end of the upper of them being pivotally connected with the lower end of said operating rod, a third link one end of which is pivotally supported within said pump body, and the other end of which is pivotally connected with the lower end of the lower one of said two links, a cover for closing the lower end of said body part, a spring acting between said cover and said third link to swing said link upward about its pivotal support, and a shaft rotatable in the bearing aforesaid and the inner end of which has a cam which acts upon the upper side of said third link to swing it downward about its pivotal support.

In testimony whereof I affix my signature.
ABRAHAM M. BABITCH.
